CLAIM

The ornamental design for a bone screw, as shown and described herein.

DESCRIPTION

FIG. 1 is a perspective view of a bone screw in accordance with the present invention.

FIG. 2 is a perspective view of the bone screw of FIG. 1. FIG. 3 is an elevational view a first side of the bone screw of FIG. 1.

FIG. 4 is an elevational view of a second side of the bone screw of FIG. 1.

FIG. 5 is a plan view of a proximal end of the bone screw of FIG. 1; and,

FIG. 6 is a plan view of a distal end of the bone screw of FIG. 1.

The broken line showing is included for the purpose of illustrating unclaimed subject matter and forms no part of the claimed design.
